UNITED STATES PATENT OFFICE.

JACOB E. DUELKS, OF BOSTON, MASSACHUSETTS.

LOOM.

1,388,808.

Specification of Letters Patent. Patented Aug. 23, 1921.

Application filed October 22, 1920. Serial No. 418,696.

To all whom it may concern:

Be it known that I, JACOB E. DUELKS, a citizen of the United States, residing at Readville, Boston, in the county of Suffolk 5 and State of Massachusetts, have invented new and useful Improvements in Looms, of which the following is a specification.

My present invention relates to improvements in looms of the kind used in the weaving of fabrics of various kinds having interwoven warp and weft threads and it pertains more particularly to the shuttle mechanism thereof. The primary object of the invention is to provide novel and improved 15 mechanism, whereby a more certain pick is secured, the mechanism is relatively compact and light in weight, it requiring relatively small space on the loom, it avoids or reduces to a minimum the wear and tear on 20 the loom and its parts, especially the picker mechanism, and it otherwise insures a more economical and efficient operation of the loom.

To these and other ends, the invention 25 consists in certain improvements and combinations and arrangements of parts, all as will be hereinafter more fully described, the features of novelty being pointed out particularly in the claims at the end of the specification.

In the accompanying drawing:—

Figure 1 is an elevation of a picker mechanism mounted on the left hand end of the lay of a loom;

35 Fig. 2 is a top plan view of the shuttle mechanism shown in Fig. 1;

Fig. 3 is an end elevation of the shuttle mechanism shown in Fig. 1, as viewed from the right;

40 Fig. 4 is a detail sectional view of the picker locking and releasing device; and

Fig. 5 represents an end elevation of the picker locking and tripping device as viewed from the left in Fig. 4.

45 Similar parts are designated by the same reference characters in the several views.

Picker actuating mechanism embodying the present invention is applicable generally to looms of various kinds, such, for example, as those used on broad silk, woolen, worsted and cotton. The preferred embodiment of the invention is shown in the accompanying drawing and will be hereinafter described in detail. It is to be understood, 50 however, that the invention is not restricted

to the precise construction shown, as equivalent constructions are contemplated and these will be included within the scope of the claims.

In the present instance, the numeral 1 represents one end of the lay of a loom and which, as well understood in this art, has a to-and-fro movement in a direction longitudinally of the loom or the warp threads, the lay usually swinging about a definite transverse axis. The shuttle 2 which contains the warp threads and is alternately carried by the picks of the loom through the shed formed by the warp threads, travels across the loom, guided by the lay in any suitable 60 or well known manner, each throw of the shuttle taking place under the impulse of a picker 3 which may be of any suitable or well known construction. It will be understood that a picker-driving mechanism is 65 provided at each side of the loom or at each end of the lay, and these mechanisms may be of substantially duplicate construction, except that they impart reverse impulses to the shuttle to effect the necessary reciprocating movements thereof. Each shuttle-driving mechanism comprises a picker shaft 4 which is guided by suitable bearings 5 in a bracket 6, so as to reciprocate in a direction 70 transversely of the loom or longitudinally 75 of the lay, the bracket 6 being bolted or otherwise fixed to the lay, so that it projects laterally beyond the side frame of the loom. The picker 3 is connected to the picker shaft 40 by an arm 7, and in order to prevent rebound 80 of the shuttle upon striking the picker and to minimize shock due to the impact of the shuttle against the picker, this arm 7 is preferably splined on the picker shaft so that it 85 may have a limited movement longitudinally thereof, and a compression or shock-absorbing spring 8 is interposed between the outer side of this arm and a retaining or adjusting nut 9 on the picker shaft. The picker shaft 90 is provided with one or more key-ways 10 to coöperate with keys in the bearings 5, so that while this shaft may reciprocate longitudinally, it will be held from rotation. The operating or shuttle-driving strokes of the 95 picker shaft are effected by a suitable spring, the spring 11 employed for this purpose in the present instance being a tension spring and having one end fixed at 12 to a part of the fixed bracket 6 and having its opposite end attached at 13 to a collar 14, the latter 100

110

being clamped or otherwise fixed on the picker shaft, so that the tension of the spring 11 acts to force the picker shaft toward the right in Figs. 1 and 2. The collar 14, when 5 the picker shaft is fully retracted, may abut against a part of the bracket 6, as shown in Figs. 1 and 2, it thus acting as a stop to limit the return strokes of the picker shaft. The picker shaft is locked or otherwise held 10 in its retracted position and is released at the proper moment, by a dog 15 which has a blade arranged to enter a notch 16 in the picker shaft, when the latter is fully retracted, the dog being normally forced 15 toward the picker shaft by a spring 17 and the dog having a shank or stem 18 which is guided to reciprocate in a part of the bracket 6. The dog is also provided with an eye 19, into which fits an end of a controlling lever 20, the latter being provided at 21 on a part 20 of the bracket 6, and having its opposite end 22 projecting into a position where it may be acted on by a releasing device, which will be hereinafter described.

25 The picker shaft is periodically retracted, preferably by a gear 23, which has a gear segment 24 extending around a part of its circumference and arranged to coöperate with a toothed rack 25 on the picker shaft, 30 so that each revolution of the gear 23 will cause the gear segment 24 to coöperate with the rack 25 (assuming that the picker shaft has made a stroke to drive the shuttle) and the retracting action of the gear 23 continues. 35 until the picker shaft reaches a position where the notch or slot 16 therein registers with the dog 15, whereupon the latter will snap into the notch or slot 16 and at the same moment the rear end of the gear segment 40 24 will pass off of the rack 25. The collar 14 will prevent overthrow of the picker shaft on its return stroke. The gear 23 is fixed on a shaft 26 which is journaled in suitable 45 bearings on the frame 6, and it is connected by beveled gears 27, or equivalent means, to a shaft 28, which shaft is also journaled in suitable bearings on the frame 6. The shaft 28 serves to drive the gear 23 and it also controls the tripping of the picker shaft. For 50 these purposes, it is provided at one end with an arm 29 which is fixed thereto at the proper angle and this arm carries a lifter finger 30, which rotates in the plane at the end 22 of the controlling lever 20, and the shaft 28, 55 at a certain part of its forward rotation, brings the lifter finger 30 up against the end 22 of the controlling lever, thus rocking the latter and causing the dog 19 to release the picker shaft, permitting the latter to impel 60 the picker on its shuttle-driving stroke under the action of the spring 11. Preferably, the lifter finger 30 is hinged, as shown, so that it may bend over and thus clear the controlling lever, thus avoiding tripping of the picker 65 shaft, so that the shuttle may remain in the

shuttle box, should it become necessary for any reason to reverse the direction of rotation of the picker-driving mechanism.

Preferably, the to-and-fro movements of the lay relatively to the fixed frame of the loom are utilized to tension the actuating spring for the picker shaft and to trip the picker shaft at the appropriate time. As shown, a rack bar 31 is fixed by a bracket 32 to the respective side frame of the loom, this rack having curved racks 33 and 34 on its upper and lower sides which are concentric with the axis about which the lay swings. A pair of gears 35 and 36, which are of the same pitch diameter, are arranged to coöperate with the upper and lower racks 33 and 34 and these gears each revolve once to each pick of the shuttle. These gears 35 and 36 are fixed to revolve with pinions 37 and 38, the latter being journaled on studs 39 and 40, which are fixed to the bracket 6, and they coöperate with an interposed pinion 41 which is of the same pitch diameter and is journaled on a stud 42 fixed to the bracket 6. The pinion 41 meshes with a gear 43 which is 90 twice the diameter of the pinion 41 and this gear 43 is fixed to the shaft 28. By the construction just described, it will be understood that for each pick of the shuttle, the gears 35 and 36 and in consequence, the pinion 41 will revolve once, and owing to the 2 to 1 ratio of transmission between the pinion 41 and the shaft 28 and the equal gear ratio connecting the shaft 28 to the shaft 26, the gear 23 will rotate a half revolution to each 95 pick. The gears 35 and 36, however, are interrupted gears, their toothed peripheries including about one-half their circumferences and these gears are set in reverse relation to the rack bar 31, so that while the gear 36 engages the toothed rack 34, the gear 35 will be out of engagement with the rack 33, and vice versa. Owing to the interposed pinion 41 which connects the pinions 37 and 38 which are attached to the gears 35 and 36, 100 the latter gears are caused to revolve in the same direction. In consequence, one of the gears for example, the gear 36, will be driven in a forward direction by the throw of the lay in one direction, due to the rolling of its gear 105 surface on the lower rack 34, and when the end of the throw of the lay is reached, the toothed part of the gear 36 will pass off of the toothed rack 34 and the toothed part of the gear 35 will become engaged with the upper 110 toothed rack 33, and the return motion of the lay will cause the gear 35 to be driven in a forward direction, the upper gear 35 being disengaged with the upper rack and the lower gear 36 becoming engaged with 115 the lower rack, when the lay reaches the end of its return stroke. By this arrangement, the shuttle-driving mechanism is maintained 120 in proper timed relation to the throws of the lay, the shuttle-driving mechanism is always 125 130

driven forwardly, although the lay has a reciprocating movement, and furthermore, the gears 35 and 36 become engaged and disengaged relatively to their respective racks 33 and 34, without jar, shock or noise. It will also be understood that the gears 23 of the picker mechanism at opposite sides of the loom, will be set in reverse relation; that is to say, the gear segment 24 of the gear 23 at one side of the loom, will be diametrically opposite to the corresponding gear segment at the opposite side of the loom, in consequence of which, the picker mechanisms at opposite sides of the loom will pick the shuttle alternately. Each picker is driven by its spring, after the same has been tripped by withdrawal of the dog 15, and when the picker has reached the end of its stroke, the rack 25 on the picker shaft will be in a position to be engaged by the gear segment on the spanning gear 23, and the forward rotation of this gear retracts the picker until it latches and becomes locked by the dog 15.

Obviously the mechanism herein shown and described may be used on a shuttle-change or box-loom, by providing each spanning gear 23 with two gear segments 24, which will be located at diametrically opposite points, and by providing each shaft 28 with a second lifter finger, which will be located diametrically opposite to the lifter finger 30 shown.

Shuttle-operating mechanism constructed in accordance with the present invention is positive and certain in its action and it imparts swift picker strokes to the shuttle so that it is particularly applicable to looms used for the weaving of relatively wide fabrics. Although the shuttle strokes are swift, the impulses or picks are imparted to the shuttle substantially without impact between the picker and the shuttle, the speed with which the shuttle is driven being derived from the accelerating action of the actuating spring, and in consequence, the wear and tear on the loom and particularly the pickers is greatly reduced and the loom operates without shock or noise, or substantially so. Moreover, the loom is capable of operating at increased speed, and by avoiding the use of the usual picker sticks, the usual cause for the frequent replacement of parts is eliminated.

I claim as my invention:

1. In a loom having a lay and a main frame, picker mechanism comprising a picker shaft, a spring for actuating the same on its shuttle-driving stroke, and direct gearing continuously connecting the lay and main frame and driven directly and continuously by the beats of the lay in both directions to retract said shaft against its spring and to release it to be driven forward on its shuttle-driving stroke by said spring.

2. In a loom having a lay, picker-operat-

ing mechanism comprising a picker-driving member, a spring operative to actuate the picker-driving member on its shuttle-picking stroke by power stored in such spring, and means including a member movable continuously and always in the same direction by and in consequence of the to-and-fro beats of the lay and operative periodically to store power in said spring.

3. In a loom having a lay adapted to beat to-and-fro, picker-operating mechanism comprising a picker-driving member, a device capable of storing power therein when the picker-driving member is retracted, which power is sufficient to impart a pick to the shuttle, and means including a member driven continuously and unidirectionally by the beats of the lay and operative periodically to store such power in said device.

4. In a loom having a lay, shuttle-operating mechanism comprising a picker shaft, a device coöperative therewith capable of storing power sufficient to impart a pick to the shuttle, means for restoring said shaft to a normally retracted position and for thus storing such power in said device, a dog movable automatically into locking engagement with the picker shaft when the latter has been fully retracted, and gearing forming a motion-transmitting connection between the lay and the main frame and driven by and in response to the beats of the lay for periodically operating said restoring means and subsequently retracting said dog.

5. In a loom, shuttle-operating mechanism comprising a reciprocating picker-shaft having a picker associated therewith, a spring acting to drive said shaft in one direction, a rack connected to the shaft, a gear segment coöperative with the rack to retract the picker-shaft after the latter has been driven by said spring and disengaging from said rack while said shaft is in retracted position, and means for holding the picker-shaft in retracted position and for releasing it.

6. In a loom, shuttle-operating mechanism comprising a reciprocating picker-shaft having a picker associated therewith, a spring acting to impel said shaft on its shuttle-picking stroke, a rack connected to the picker-shaft, a gear segment rotatable in one direction and coöperative with said rack when the picker-shaft has made a shuttle-picking stroke to restore said shaft, the gear segment disengaging from the rack when the picker shaft has been restored, and means for releasably holding the picker shaft in restored position.

7. In a loom, driving means for the shuttle-operating mechanism thereof, comprising a rack bar having means for fixing it to the main frame of the loom and a pair of coöperative gears having means for mounting them on the swinging lay, the rack bar having a pair of racks to coöperate with the re-

spective gears, and the gears having reversely-positioned interruptions to cause alternate engagement of the gears with the respective racks, and means driven unidirectionally by said gears.

8. In a loom, driving means for the shuttle-operating mechanism thereof comprising a pair of racks, a pair of gears reciprocable in unison longitudinally of the racks and 10 respectively coöoperative therewith, said gears having interrupted portions to cause alternate engagement of the gears with the respective racks during the relative recipro-

cating movements between the racks and the gears, and gearing connecting said gears to 15 cause simultaneous rotation thereof in the same direction, said gearing being driven unidirectionally by said gears.

In testimony whereof I have hereunto set my hand in presence of two subscribing witnesses.

JACOB E. DUELKS.
